UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

YARN TENSION FOR WINDING-MACHINES.

1,307,701.

Specification of Letters Patent. Patented June 24, 1919.

Application filed October 5, 1918. Serial No. 256,947.

To all whom it may concern:

Be it known that I, ALONZO E. RHOADES, a citizen of the United States, and resident of Hopedale, county of Worcester, State of Massachusetts, have invented an Improvement in Yarn Tensions for Winding-Machines, of which the following description, in connection with the accompanying drawing, is a specification, like characters on the drawing representing like parts.

This invention relates to improvements in yarn winding machines and the object thereof is to provide means for maintaining a more even tension upon the yarn as it is wound upon the yarn receiving means and also of more effectively guiding the running strand as it approaches said yarn receiving means.

More specifically the invention relates to improvements in spoolers or winding machines of like character in which a spool or other yarn receiving means rotated by suitable mechanism draws the yarn from a yarn supplying means such as a bobbin or cop 25 suitably supported in fixed relation to the spooler, the traverse of the yarn upon the spool being effected by a vertically reciprocating traverse rail which is provided with a suitable guide for laying the running strand 30 upon the spool.

In yarn winding machines of this character the vertical reciprocation of the traversing mechanism causes a considerable variation in the length of the strand between the 35 yarn receiving means and the yarn supplying means, thereby providing a variation in the speed with which the yarn is drawn by the yarn receiving means from the yarn supplying means. This causes a variation in 40 the tension upon the running strand. Where the yarn supplying means is in the form of a bobbin or cop having a "filling wind" this variation in the tension on the running strand is accentuated by reason of the conoidal form of the windings.

The principal object of the present invention is to provide means for insuring a uniform tension upon the running strand as it is wound upon the spool and this is accomplished in the invention by locating the tension device closely adjacent to the spool or other yarn receiving means. The tension device thus located preferably is carried by the traversing mechanism and is positioned between said traversing mechanism and the

body of the spool or other yarn receiving device. By placing the tension device between the traversing mechanism and the yarn receiving means a uniform tension is always maintained upon the strand as it leads to the 60 spool or other yarn receiving means notwithstanding variations in the tension of the yarn as it comes from the yarn supplying means.

A further object of the invention is to provide a tension device which acts to remove or crush any motes, bunches or kinks which may pass through the guide and clearer of the traversing means.

A further object of the invention is to 70 provide a yarn winding machine which shall impose a uniform tension upon each of the running strands leading to the respective yarn receiving means, and this preferably is accomplished by partly supporting a weight 75 upon each of the running strands between the traversing mechanism and the yarn receiving means.

By providing weights of different size the mechanism may be adapted for use with different kinds of yarns and for different tensions, but with use of the same weights throughout the machine a uniform tension upon all of the running strands, will be maintained.

A further object of the invention is to provide a tension device of the character above specified which may be applied to usual commercial forms of yarn winding machines without material modification of 85 the machines.

Other objects and features of the invention will more fully appear from the following description and the accompanying drawings and will be pointed out in the annexed 90 claims;

In the drawings;

Figure 1 is a transverse section of a sufficient portion of the spooler to illustrate the application of the present invention thereto, 100

Fig. 2 is a plan view of the guide and clearer and a preferred form of tension which is adapted to be located between said guide and clearer and the yarn receiving means,

Fig. 3 is a side view of the same,

Fig. 4 is a vertical sectional view of the tension means on lines 4-4, Fig. 3, the weight however being shown in elevation, and,

Fig. 5 is a similar view showing a weight of a different size in vertical section.

The yarn winding machine which is illustrated in the drawing is a spooler of a usual type comprising a frame 1 in which is seated a series of spool carriers or spindles 2 carrying the spools 3 and driven by whorls 4 in the usual manner from belts passing around the central rotating drum 5. The 10 yarn supplying means which is illustrated herein in the form of a "filling wound" bobbin or cop 6, is supported upon a spindle 7 carried by an arm 8 at the bottom of a bracket 9 which is clamped to a rod 10 extending longitudinally of the frame of the machine. The bracket 9 is provided with an arm 11 which extends in substantial parallelism with the spindle 7 and is provided at its ends with a laterally extending fork 12 which serves as a guide for directing the 20 yarn from the end of the supplying means.

The traverse of the yarn upon the spools is effected through yarn guiding devices carried by a traverse rod 13 which is reciprocated by the arms 14 through the yoke 15 in the usual manner. The guiding means for directing the running strand to cause the same to traverse the spool may be of any suitable type which will permit the placing 30 of a tension device between such guiding means and the spool or other yarn receiving means so that the tension device may be located closely adjacent to the body of the spool. A desirable form of combined guiding means and tension mechanism is illustrated herein and comprises a bracket having a body portion 17 which has a partially cylindrical recess 18 to engage the traverse rod 13 and a clamping member 19 provided 40 with a complementary cylindrical recess 20, said clamping member being secured to the body member 17 by a set screw 21, so that the bracket may be clamped at any desired position on the traverse rod 13.

45 The body portion 17 of the bracket has an upwardly extending arm 22 which forms a stationary member of the clearer guide for the traversing mechanism. The body portion is also provided with a downward extension in which a stud 23 is secured by a set screw 24. The stud 23 provides a support for an L-shaped counterweighted arm 25, the upwardly extending member of which has a recess to receive a rib upon the guiding member 26, the guiding member 26 being secured to the arm 25 by a set screw 27 passing through a slot in said arm into the lower portion of the guiding member 26. The guiding members 22 and 26 desirably have 55 converging curved edge portions 28 and 29 which merge into inclined parallel walls which form a slot 30 through which the yarn passes to the yarn receiving means.

By adjusting the movable member 26 the 60 walls of the slot may be positioned in ac-

cordance with the size of yarn being spooled and serve not only to guide the yarn but also to strip from it motes, burs, etc., in the usual manner.

It will be understood that other forms of 70 traverse guides and clearers may be employed and that the above construction is a preferred mechanism to which I have applied my invention.

In the preferred embodiment of the invention illustrated herein the body portion of the bracket has a lateral extension 31 which has a smooth weight supporting surface 32 preferably somewhat inclined to the horizontal when the bracket is fastened to 80 the traverse rod 13. A stud 33 extends normal to the central portion of the weight supporting surface 32. A longitudinally apertured weight 34 rests at its bottom upon said surface 32 and is mounted loosely on 85 the stud 33, the aperture in the weight being of larger diameter than the stud.

The extension 31 desirably projects a short distance beyond the weight supporting surface and has secured to it a pin or 90 guide 35 provided with a curved end 36. The weight 34 is desirably in the form of a frustum of a cone having a beveled or curved bottom edge 37 to avoid cutting or abrading the strand running beneath the weight. 95

Weights of different sizes may be employed to provide means for supplying different degrees of tension, such as may be required by different kinds of yarn or different windings upon the yarn receiver. Fig. 5 100 shows a weight 34^a of a larger size and hence capable of producing a greater tension.

The weights 34 may be protected especially against accidental or careless removal and loss by an inclosing casing 38 conforming substantially in contour to the weights 34, having an open bottom and a top 39 providing a head which may be screwed down upon the stud 33 and secured 110 at any desired point thereon by a set nut 40.

In the operation of the machine the running strand of yarn 42 is carried from the yarn supplying means 6 through the forked end 12 of the bracket 9, thence through the 115 slot 30 between the pivoted and stationary clearer members or guides 22, 26, thence downwardly around the stud 33 beneath the bottom of the weight 34, thence over the guide 35 to the spool or other yarn receiving 120 means.

The weight therefore is partially carried upon the strands of yarn between the guiding or clearing members of the traverse mechanism and the spool or other yarn receiving means so that the tension is applied to the running strand of yarn as closely as possible to the point at which it is being wound upon the spool. This causes a uniform tension upon the yarn at all times not 125 130

withstanding the difference in the speed at which the yarn is drawn from the yarn supplying means as the traverse bar is raised and lowered.

- 5 The weight 34 by being loosely mounted upon the stud 33 rotates as the running strand of yarn is drawn beneath its base so that any motes, bunches or kinks which may have passed through the slot 30 between the 10 guiding or clearing means 22 and 26 on the traversing mechanism will be ironed out before they reach the spool.

It is to be understood that the embodiment of the invention disclosed herein is 15 illustrative and not restrictive and that various modifications may be made within the meaning and scope of the following claims.

Having thus described my invention what I claim as new and desire to secure by Letters Patent is:

1. In a yarn winding machine comprising means for rotating a yarn receiving means to draw yarn from a yarn supplying means carried by a stationary support, a traverse 25 rail, means located between the traverse rail and the yarn receiving means, and closely adjacent the latter, acting to apply a uniform tension to the short portion of the running strand being traversed, whereby 20 the uniform tension will be imposed upon the strand as it is wound upon the yarn receiving means, irrespective of variations in the tension upon the yarn between the traverse rail and the yarn supplying means.

- 35 2. In a yarn winding machine comprising means for rotating a yarn receiving means to draw yarn from a yarn supplying means, a traverse rail, a clearer guide and a tension device located between said traverse 40 rail and the yarn receiving means and acting to apply a uniform tension to the short portion of the running strand being traversed, irrespective of variations in the tension upon the yarn between the traverse rail and the 45 yarn supplying means.

3. In a yarn winding machine comprising means for rotating a yarn receiving means to draw yarn from a yarn supplying means and reciprocating means for causing 50 a traverse of the yarn upon the yarn receiving means including a clearer guide for the running strand carried by said reciprocating means; a plate having a stationary yarn engaging surface located between said 55 clearer guide and the yarn receiving means, a cooperating weight resting upon said plate and means for guiding the running strand between said plate and said weight whereby the weight will be partially supported by

the running strand and a uniform tension 60 applied to the short portion of the running strand being traversed and leading to the yarn receiving means irrespective of the variations in tension upon the yarn as it comes from the yarn supplying means. 65

4. In a yarn winding machine comprising means for rotating a yarn receiving means to draw yarn from a yarn supplying means and means for causing a traverse of the yarn upon the yarn receiving means including a guide for the running strand; an inclined plate having a yarn engaging surface located between said guide and the yarn receiving means, a stud extending upwardly normal to said yarn engaging surface, a weight slidably and rotatably mounted upon said stud and means for guiding said strand around said stud beneath said weight.

5. In a spooling machine comprising a series of spool supports and means for rotating the same, a complementary series of bobbin spindles, a traverse rail having guides for the strands of yarn running from the bobbins to the spools and means for reciprocating said traverse rail; means for maintaining a uniform tension upon each and all of the running strands comprising a series of weight supporting surfaces carried by said rail and located between said rail 85 and the respective spools and closely adjacent to said spools, uniform weights carried by said weight supporting surfaces and means for guiding said strands beneath said weights to said spools.

6. A combined traverse guide and tension for spooling machines comprising a bracket having a lateral extension presenting a stationary yarn engaging surface, a stud extending upwardly therefrom normal to said surface, a weight slidably and rotatably mounted upon said stud and means for guiding the yarn over said stationary surface beneath said rotatable weight.

7. A combined traverse guide and tension for spooling machines comprising a bracket having yarn guiding members and a lateral extension having a yarn engaging surface, a stud extending upwardly therefrom normal to said surface, a weight rotatably and slidably mounted upon said stud, a cover substantially inclosing said weight and means for adjustably supporting said cover upon said stud.

In testimony whereof I have signed my 115 name to this specification.

ALONZO E. RHOADES.
